UNITED STATES PATENT OFFICE.

HENRY BRUNT, OF BALTIMORE, MARYLAND.

DESIGN FOR A COVERED DISH.

SPECIFICATION forming part of Design No. 21,128, dated October 27, 1891.

Application filed August 8, 1891. Serial No. 402,179. Term of patent 3½ years.

To all whom it may concern.

Be it known that I, HENRY BRUNT, a citizen of the United States, residing at Baltimore, Maryland, have invented and produced 5 a new and original Design for a Covered Dish, of which the following is a specification, reference being had to the accompanying drawings, forming a part hereof.

Referring to the drawings, Figure 1 is a perspective view of the dish and cover. Fig. 2 is a top, and Fig. 3 a front, view of the same. I describe the dish proper as follows: Its base A as seen from the bottom is elliptical. The body B is also elliptical and rises from 15 the base in an expanding curved line until the greatest diameter at C is obtained, when it curves suddenly inward, as at D. From this point begins the upper edge E, which flares outward, and as seen from the top it 20 has a general elliptical outline the same as the body, except that it is somewhat elongated. (See Fig. 2.) The continuity of the elliptical lines of the body and the flared edge

is interrupted or broken by the curved depressions *a* in the body and *b* in the edge. The handles commence from and are a continuation of the edge F at the greatest diameter, and in falling toward the body, to which they are connected by a flower in relief, pass from the center of the dish to one side thereof. The 25 angle of departure from a vertical line is reversed in the two handles, one passing to the right and the other to the left side. These handles are suitably decorated. The cover has the curved depressions *c*, which break the 30 continuity of the ellipse the same as the body. The handle rises from a flower in relief and terminates in a foliated end, which touches the top of the cover.

I claim—

The design for a covered dish, as herein shown and described.

HENRY BRUNT.
